(57) **CLAIM**

The ornamental design for a fiberglass insulation board packaging, as shown and described.

DESCRIPTION

FIG. 1 is perspective view of a fiberglass insulation board packaging showing my new, original and ornamental design; FIG. 2 is top view thereof; FIG. 3 is bottom view thereof; FIG. 4 is front view thereof; FIG. 5 is back view thereof; FIG. 6 is right side view thereof; and, FIG. 7 is left side view thereof.

The broken lines in the drawings show portions of the fiberglass insulation board packaging which form no part of the claimed design.

1 Claim, 5 Drawing Sheets
